UNITED STATES PATENT OFFICE.

ORED OLSSON, OF ORD, NEBRASKA.

WINDMILL.

SPECIFICATION forming part of Letters Patent No. 626,559, dated June 6, 1899.

Application filed October 22, 1898. Serial No. 694,318. (No model.)

To all whom it may concern:

Be it known that I, ORED OLSSON, of Ord, in the county of Valley and State of Nebraska, have invented a new and Improved 5 Windmill, of which the following is a full, clear, and exact description.

My invention relates to improvements in windmills of that type in which the vanes are made automatically adjustable in angle and 10 are controlled by a governor, which is mounted directly upon the mill.

My invention comprises the novel construction of the vanes and wheel, as well as the peculiar form of governor and the means for 15 controlling the governor and connecting the same with the vanes.

The invention also comprises the novel features hereinafter described and claimed.

Reference is to be had to the accompanying 20 drawings, forming a part of this specification, in which similar characters of reference indicate corresponding parts in all the figures.

Figure 1 is an elevation of my windmill, showing an edge view of the wheel. Fig. 2 is an 25 elevation of the pivoting frame upon which the wheel is mounted, the view being at right angles to that of Fig. 1. Fig. 3 is a side view of the wheel in the direction of the arrow α in Fig. 1, the supporting-shaft being in section. Fig. 4 is an enlarged view of the collar which surrounds the central shaft and to 30 which the vane-guys are attached. Figs. 5 and 6 are transverse sections taken, respectively, upon the lines 5 5 and 6 6 in Fig. 1. Fig. 7 is a transverse section taken upon the 35 line 7 7 in Fig. 8. Fig. 8 is a longitudinal sectional elevation through the axis of the wheel. Figs. 9 and 10 are transverse sectional views of two adjacent vanes, showing 40 the connection of the governor thereto and of the links by which the vanes are all moved simultaneously to dispose them at varied angles toward the wind. Fig. 11 is a transverse sectional view through one vane and center shaft, 45 taken upon the line 11 11 in Fig. 12 and showing other details connected therewith. Fig. 12 is an enlarged fragmentary side view of a portion of one vane and the controlling connections thereto, taken in the direction of the 50 arrow α in Fig. 1. Fig. 13 is a similar view taken from the opposite side of the vane, and

Fig. 14 is a transverse sectional view taken upon the lines 14 14 in Figs. 12 and 13.

My windmill has been designed in such a manner that it may be constructed entirely 55 of iron and steel, is entirely automatic in its action, and is so mounted as to obviate the necessity for a regulating-vane, the mill being so mounted relatively to its pivot that it will at all times swing to such a point that it 60 will face the wind. The mill is also provided with a governor so connected with the vanes that they will be turned at an angle to the wind corresponding with its speed and in extremely-high winds will turn the flat blades 65 or vanes so that they present much less surface to the wind. The mill is supported upon a frame A, provided with a vertically-depend- 70 ing sleeve A', (see Fig. 8,) said sleeve entering a journal-bearing in a casing C, supported upon the upper end of a tower or other support (not shown) for the windmill. The lower end of this hollow journal or sleeve is pro- 75 vided with an extension, to which is secured a block a' or other device, which will prevent its being lifted out of its bearing. Upon an upright arm of the frame A a horizontally-extending sleeve A² is formed or affixed, through which passes the shaft D of the wind- 80 mill. On an upright extension from the arm mentioned a horizontally-extending sleeve A³ is formed, through which passes the journal-shaft of a crank-gear B, which meshes with a pinion B', secured to the end of the shaft D. The crank-gear B is connected, by means of 85 a link B², with the pump-rod B³, which passes downward through the central hole in the journal-sleeve A' and is connected by any suitable means with the pump or other mech- 90 anism which the wheel operates. The upper 95 end of the pump-rod B³ is controlled in its motion by means of a link B⁴, which is connected thereto and to the outer end of an arm A⁵, forming a part of or connected with the movable frame A. The hole in the journal- 100 sleeve A' is of such size as will permit a proper rocking motion of the link B² and the pump-rod B³.

In loose contact with the rear end of the sleeve A² is a hub D', keyed or otherwise se- 100 cured upon the shaft D and forming the hub of the wind-wheel. Secured to this hub and

extending radially therefrom are the arms E of the wind-wheel, which, as herein shown, are constructed of iron pipes. The flat vanes, which are pivotally mounted upon the outer portions of these arms, each consist of a plate of metal G, which has its side edges formed with laterally-projecting flanges g and also has a hollow rib g' formed thereon, these ribs and flanges serving to materially stiffen the plate and prevent its being deformed. Extending across the inner or narrow end of such vane is a flat metal bar K, which is riveted or otherwise secured thereto and in its central portion has a loop K' formed therein of such size as to receive the arm or spoke E and have a loose bearing thereon. Near the outer end of the vane is a similar bar G', which is also provided with a loop G², (see Fig. 14,) said loop extending through a narrow slot in the vane and about the spoke or arm E of the wheel, forming a second pivot-bearing. The vane is also stiffened by a flat bar of metal G³, secured to the opposite side of the vane and extending over the outer pivot-bearing in the manner shown in Figs. 12 and 14. This forms a species of truss and makes the vane very stiff. The spokes or arms E are provided with collars I and I², secured to their outer ends one on each side of the loop G², thus holding the vane in proper place upon the arm. The collar I is secured to the arm E by means of a bolt I', which passes through both and also serves as a pin for the links which join the various arms to each other and the guys which connect their outer ends with the central shaft, as will be further described.

Mounted upon the frame-sleeve A² at some distance from the hub D' is a collar e, which is formed in two pieces, as shown in Fig. 4, each piece being provided with two flanges e⁴, through which pass bolts e⁵. This collar is held in place by means of ribs or flanges a, which are formed upon the sleeve A². Guys E² extend from the collar e to the outer end of each of the arms E. These guys each have an eye or loop formed in the inner end, through which passes one end of the bolt I', as clearly shown in Figs. 11 and 12. The outer ends of adjacent arms or spokes E are connected with each other by means of links E', which have eyes formed in their ends, through which the bolts I' pass. One of these links E' is made in two pieces, the adjacent ends of each piece being threaded, and a turnbuckle E⁵ (see Fig. 3) is screwed thereon, so that all of the links may be tightened up.

The shaft D extends rearwardly beyond the hub D' and at its outer end is threaded and has two nuts e² screwed thereon, and a collar e' is held between the two nuts. This collar is provided with holes near its periphery adapted to receive the ends of the guys E³, which are secured to and extend from said collar to a connection with the other ends of the arms E. This connection may be made with the outer ends of the arms in any convenient manner; but, as herein shown, the

connection is made not directly with the arm, but with a loop formed in the end of one of the links E' close to its point of attachment to the arm, as clearly shown in Fig. 11. This method of construction makes a wheel-frame which is very stiff and at the same time is light and which does not furnish a large area for the action of the wind.

The hub D' has two arms D² extending oppositely and forming a pivotal support for the governor-arms d', which, as herein shown, are constructed of two pieces of bar-iron and which pass one upon each side of the arm D² and are united at each end. The exact construction of these arms is, however, immaterial, the formation thereof shown being a desirable one. The inner ends of the governor-arms are pivotally connected to the links F', which have their outer ends pivoted upon a collar f', mounted to slide upon the shaft D outside of the hub, as shown in Figs. 7 and 8. Between the collar f' and the collar e' a coiled spring F is mounted on the shaft D and presses the collar f' toward the hub D'. Between the collar f' and the hub is placed a short coiled spring f, which prevents shock at any time when the collar f' is thrown back toward the hub.

Upon the outer ends of the governor-arms are mounted adjustable weights d², which may be secured at various points and the speed of the mill thereby regulated. Each of the governor-arms is provided with a laterally-extending arm d³, which is connected by means of a link d⁵ with a projecting end of the bar G', secured to a vane G, as before mentioned. One edge of each vane G, to which a respective governor-arm is directly connected, is secured to the corresponding edge of an adjacent vane upon one side thereof by means of a link H, and this latter vane is secured by a similar link H to the corresponding edge of the vane next adjoining. This divides the vanes into two sets, each set including one-half of the vanes operated, respectively, by an appropriate governor-arm. It is not desirable to connect all of the vanes directly with each other by their edges, as the points of connection of the links with the vanes is at a greater distance from the shaft when in working position, as shown in Fig. 1, than when thrown out of gear, and consequently the periphery of a circle passing through these points is greater when the vanes are in one position than when they are in another. By reason of the fact that the connection of these links with the vanes is at a greater distance from the arms E at one end than at the other and that there are two breaks in the continuity of the connection the trouble which would otherwise arise is in a measure corrected. It is evident that under the action of the governor all of the vanes will be turned simultaneously, so as to present the same inclination to the wind. In Fig. 1 the governor and the vanes are shown in the position which they would occupy when

the wheel is stationary or running at a low rate of speed. In this position the vanes assume a maximum angle to the direction of the wind-current and the governor-arms are disposed at less than a right angle with regard to the axis of the shaft D. As the speed of the mill increases the weights upon the governor-arms will tend to fly outward and to draw the arms into the position shown in Fig. 8 or substantially in the same plane with the axis of the main shaft D. This is the position which the governor and the vanes occupy when the mill is thrown into inoperative position or when subjected to the pressure of a very strong wind-current, as in this position the vanes lie substantially in the direction of and present but little more than their edges to the wind. Hence the rotative effect is very greatly reduced. In order to be able to control the speed of the mill or to stop it by hand, the inner ends of the governor-arms are connected by means of links F² to a ring F³, which lies within a peripheral groove in a collar F⁴, said collar being mounted to slide upon the sleeve A². The sleeve A² has a longitudinally-extending groove J' on one side, and within this groove lies a rod J, which is secured at one end of the collar F⁴. The rod J is connected by means of a link J² to one end of a bell-crank lever J³, said bell-crank lever being pivoted upon the end of an arm A⁴, secured to or forming a part of the frame A, which carries the mill. To one end of the bell-crank lever J³ is connected a wire or cord J⁴, which extends downward through the central opening in the sleeve A' to the ground, where it may be manipulated to control the mill. By pulling downward upon the wire J⁴ the collar F⁴ is slid toward the hub and the governor-arms are thrown into the position shown in Fig. 8, the vanes at the same time being turned so as to present their edges toward the wind. In this position the mill will not run in any ordinary wind. The adjustment may be so made that it will be impossible for the mill to turn in any way.

The lateral limb d³ on each governor-arm d' is connected by a link H' with the outer edge of one of the arms E of the wind-wheel, said link acting as a guide for the governor-arm and holding the latter against lateral movement. An extension d⁴ of the arm d³ is provided with a hook so located that it will engage one of the links E' and limit the movement of the governor-arm when the latter is in one extreme position, said position being the one occupied by the mill when not running in a light wind, which position is shown in Fig. 1. The direction of the action of the wind upon the mill is shown by the arrows in Figs. 1 and 8. The wheel thus lies at one side of its pivot-point, and the wind acting upon the wheel will serve to turn it upon its pivot, so as to make it at all times face the wind. It is thus unnecessary to have a regulating-vane for this purpose. All the parts

of this mill have been made of iron, so that it will not quickly wear out or become broken. The construction of all the parts is also such that if broken or lost they may be readily replaced by any ordinary blacksmith. All the wearing parts of the mill have also been made very large, so that the amount of wear will be inappreciable and the mill will consequently be long-lived. The mill can also be dismembered, and no part is of such great size as to prevent easy transportation.

Having thus fully described my invention, I claim as new and desire to secure by Letters Patent—

1. A windmill, having spokes and vanes mounted to turn on the spokes, connections between the vanes to turn them all together, links connecting the spokes, governor-arms pivoted upon and turning with the mill, and limiting-hooks upon the governor-arms, adapted to engage the links when the vanes are in one limiting position, substantially as described.

2. In a windmill, a frame or standard having a horizontal arm provided with a shaft-bearing extending lengthwise of the same, a wheel-shaft within said bearing, a wheel mounted on the shaft, a collar journaled outside the horizontal arm of the frame and held against longitudinal movement thereon, and guys extending from said collar to the wheel-arms, substantially as described.

3. A windmill, having radial spokes, and vanes each consisting of a plate having a longitudinally-extending bar secured thereto, said arms each having a loop formed therein and adapted to encircle a spoke to form a pivot-bearing, said plates having holes adapted to receive said loops and through which the loops extend, substantially as described.

4. A windmill, comprising a wheel having a shaft, spokes, vanes pivoted upon the spokes, a governor comprising arms pivoted upon the wheel-frame and connected with the vanes to control their angle, a frame having a horizontally-extending sleeve receiving the shaft, said sleeve having an external longitudinally-extending groove, a ring turning upon the sleeve and held against sliding thereon, guys or braces extending from the arm to the wheel-frame, a collar slidable upon the sleeve, links connecting the collar with the governor-arms, a bar lying in the groove in the sleeve and passing through the ring and engaging the collar, and connections to said bar from the ground, whereby the bar and the collar may be slid upon the sleeve to shift the governor and vanes, substantially as described.

5. A windmill, comprising a wheel having a shaft, spokes, vanes pivoted upon the spokes, a governor comprising arms pivoted upon the wheel-frame and connected with the vanes to control their angle, a coiled spring surrounding the shaft, a collar upon the shaft and engaging one end of the spring, links connecting the collar and the governor-arms, a frame having a horizontally-extending sleeve re-

ceiving the shaft, said sleeve having an external longitudinally-extending groove, a ring turning upon the sleeve and held against sliding thereon, guys or braces extending from the arm to the wheel-frame, a collar slidable upon the sleeve, links connecting said collar with the governor-arms, a bar lying in the groove in the sleeve and within the ring and engaging the collar, and connections from the ground to said bar whereby it and the collar may be slid upon the sleeve to shift the governor and vanes, substantially as described.

6. A windmill, having radial spokes, vanes each consisting of a plate pivoted upon the spokes and having transversely-extending bars secured to the plate in pairs, one bar of each pair having a loop formed therein embracing the spoke to form a pivot and the other bowing outward to pass outside said loop, thus forming a truss-bar, substantially as described.

7. A windmill, comprising a wheel having a controlling or governor mechanism carried thereon, a frame having a sleeve receiving the wheel-shaft, and having an exterior longitudinal groove, a collar or ring mounted to

turn upon the sleeve but held against longitudinal movement thereon, guys or braces extending from said collar to the wheel, a bar lying within the groove and connected with the controlling mechanism, and means for moving said bar by hand, substantially as described.

8. A windmill, comprising a wheel having a controlling or governor mechanism carried thereon, a frame having a sleeve receiving the wheel-shaft and having an exterior longitudinal groove, a collar or ring mounted to turn upon the sleeve but held against longitudinal movement thereon, guys or braces extending from said collar to the wheel, a second collar mounted to slide upon the sleeve, connections from this collar to the controlling mechanism, a bar lying within the groove and connected with the second collar, and means for moving said bar by hand, substantially as described.
